CLAIM

The ornamental design for a portion of a housing for a rotary tool, as shown and described.

DESCRIPTION

FIG. 1 is a perspective view of a portion of a housing for a rotary tool according to an embodiment of our new design;

FIG. 2 is another perspective view thereof;

FIG. 3 is a right side elevation view thereof;

FIG. 4 is a left side elevation view thereof;

FIG. 5 is a top view thereof;

FIG. 6 is a bottom view thereof;

FIG. 7 is a front elevation view thereof;

FIG. 8 is a rear elevation view thereof; and,

FIG. 9 is a cross-section view thereof.

The broken lines shown herein are for illustrative purposes only and form no part of the claimed design.
